UNITED STATES PATENT OFFICE.

CHARLIE I. FERRILL, OF CLINTON, ILLINOIS.

GATE LATCH.

1,411,963.

Specification of Letters Patent.

Patented Apr. 4, 1922.

Application filed April 29, 1921. Serial No. 465,393.

To all whom it may concern:

Be it known that I, CHARLIE I. FERRILL, a citizen of the United States, and a resident of Clinton, in the county of De Witt and State of Illinois, have invented a new and Improved Gate Latch, of which the following is a full, clear, and exact description.

This invention relates to improvements in latches, particularly to a latch for gates, an object of the invention being to provide a gate latch which cannot be accidentally opened when stock bumps or rubs against the gate and a latch which will permit a gate to open in either direction.

15 A still further object is to provide a latch which will automatically operate when the gate is swung to from either side and a latch which will be simple and practical in construction, strong, durable and efficient 20 in use, and comparatively inexpensive to manufacture.

With these and other objects in view, the invention consists of certain novel features of construction and combinations and arrangements of parts as will be more fully hereinafter described and pointed out in the claims.

In the accompanying drawings:

Figure 1 is a view in side elevation illustrating a gate locked in closed position by my improved latch;

Figure 2 is a view in vertical section on the line 2—2 of Figure 1, the dotted lines indicating other positions which may be assumed by the yoke 8 when the gate is opened;

Figures 3, 4 and 5 are fragmentary detail views in transverse section illustrating the various positions assumed by the yoke 8 as 40 the gate is swung to;

Figure 6 is an enlarged fragmentary perspective view of the upper end of the yoke 8.

Referring in detail to the drawings, 1 represents a fence post forming one side of a 45 closure frame and 2 represents a closure in the form of a gate which is hinged to the opposite side of the frame. I have illustrated a gate which includes a plurality of horizontal rails 3 connected by upright metal braces or straps 4, the intermediate 50 rails 3 being somewhat shorter than the upper and lower rails for a purpose which will hereinafter appear.

5, 5 represent a pair of elongated U-shaped brackets, the ends of which straddle and are bolted to a pair of the shorter rails 3 and

the intermediate portions of which form loops 6 extending beyond the ends of the rails and located in vertical alignment.

Collars such as 7 are located in the loops 60 and these collars provide bearings for the ends of a vertical yoke 8. A knob 9 on the upper end of the yoke 8 rests upon the upper collar 7 and retains the yoke in place. A disc 10 fixed around the yoke just below 65 the loop 6 is formed with a recess or notch 11. A locking member 12 is pivoted in the upper bracket 5 on a pin 13 and is engageable in the notch 11 to hold the yoke against rotary movement. This lock- 70 ing member, may, if desired, be swung to inoperative position, as indicated in dotted lines in Figure 1, and be supported in this position by the knob 9.

An offset bar 14 is secured to the inner 75 face of the fence post 1. This bar has its ends attached to the post and its intermediate portion offset and located in parallelism with the post. The offset intermediate portion is widest at its center flaring to a 80 pair of pointed lugs such as 15. The bar 14 is straddled by the yoke 8 to hold the gate in closed position.

The gate automatically latches as it is swung to closed position. As illustrated in 85 Figures 3, 4 and 5, when the gate is swung to closed position, one side of the yoke 8 will strike the offset bar 14, causing the yoke to pivot or rotate and straddle the bar. The locking member 12 which is normally sup- 90 ported upon the knob 9 when the gate is open will be jarred by the impact of the yoke 8 and the bar 14 and will fall into operative locking position. Since the yoke may be disengaged from the bar only by rotary 95 motion, the locking member 12 effectively prevents opening of the gate.

Although I have illustrated one of the preferred embodiments of my invention, it will be apparent that various slight changes 100 and alterations might be made in the general form and arrangement of the parts described without departing from the invention and hence I do not wish to limit myself to the precise details set forth, but shall consider myself at liberty to make such slight changes and alterations as fairly fall within the spirit and scope of the appended claims.

I claim:

1. The combination with a closure frame 110 and a closure hingedly mounted therein, of a pivoted yoke carried by the free end of

the closure, means supported on the frame engageable with the yoke to hold the closure against opening, a notched collar carried by the yoke, and means engageable in the 5 notches of the collar to prevent accidental opening of the closure.

2. The combination with a closure frame and a closure hingedly mounted therein, of a pivoted yoke carried by the free end of the 10 closure, means supported on the frame engageable with the yoke to hold the closure against opening, a notched collar carried by the yoke, means engageable in the notches of the collar to prevent accidental opening 15 of the closure, and said means comprising a pivoted locking member.

3. The combination with a closure frame, of a hinged closure movable in the frame, a yoke rotatably mounted adjacent the free 20 edge of the closure, means rigidly attached to the closure frame engageable with the yoke when the closure is swung to closed position and adapted to be straddled by the yoke, and means for locking the yoke against

accidental rotary movement when it is in 25 locked relationship with said means, said last mentioned means comprising a notched collar rigidly attached to the yoke and a pivoted locking member engageable with the 30 collar.

4. The combination with a closure frame and a closure hingedly mounted in the frame, of an offset bar rigidly attached to the frame, a yoke rotatably mounted adjacent the free edge of the closure and normally 35 straddling said bar, means whereby rotary movement of the yoke is necessary to disengage the yoke from the bar, and means preventing accidental rotary movement of the yoke, said last mentioned means comprising a collar fixed to the yoke and having a notch therein and a pivoted locking member engageable in the notch.

5. A device of the character described in claim 4 and including means for supporting 45 the locking member in inoperative position.

CHARLIE I. FERRILL.
